UNITED STATES PATENT OFFICE.

BENJAMIN H. JONES, OF ST. LOUIS, MISSOURI, ASSIGNOR TO SMITH & DAVIS MANUFACTURING CO., OF ST. LOUIS, MISSOURI, A CORPORATION OF MISSOURI.

CORNER-FASTENING FOR BEDS.

1,385,173.

Specification of Letters Patent. Patented July 19, 1921.

Application filed January 27, 1921. Serial No. 440,389.

To all whom it may concern:

Be it known that I, BENJAMIN H. JONES, a citizen of the United States, residing at St. Louis, State of Missouri, have invented 5 certain new and useful Improvements in Corner-Fastenings for Beds, of which the following is a full, clear, and exact description, reference being had to the accompanying drawings, forming a part hereof.

10 My invention has relation to improvements in corner-pieces for bed-steeds and consists in the novel features of construction more fully set forth in the specification, and pointed out in the claims.

15 The object of the present invention is to provide a corner-fastening whereby the bed-post, side-rail and end-rails may be rigidly secured together; a further object being to secure these parts together quickly and 20 permit of their being disassembled easily and without the aid of tools.

25 A further object is to provide a bed corner-piece that may be cheaply manufactured and one that is strong and simple, this latter object being best attained by forming the corner from a stamping or pressed steel, it being one of the objects of my invention to dispense with castings which are easily broken in handling.

30 In addition to the above advantages I construct the corner-piece so that it may receive the side-rail either in its normal or reversed position.

35 Other and further advantages will be better apparent from a detailed description of the invention in connection with the accompanying drawings, in which—

Figure 1 is a perspective view of my improved corner attached to a bed-post; Fig. 2 40 is a perspective view of the end of a side rail in position to enter the corner; Fig. 3 is a vertical transverse section through the corner on the line 3—3 of Fig. 1, with the side-rail in place; Fig. 4 is a vertical longitudinal section taken on the line 4—4 of Fig. 1 with the side rail in place; Fig. 5 is 45 a vertical transverse section on the line 5—5 of Fig. 1; and Fig. 6 is a section similar to Fig. 3 with the side-rail reversed.

50 Referring to the drawings P represents a bed-post to which my improved corner is secured. The corner comprises an outer shell 1 made up from pressed steel angles 2, 2 the opposite legs of the angles being provided 55 with terminal lugs 3, 3 which traverse slots

4, 4 in the adjacent leg of the opposite angle, said lugs being riveted over as shown in Fig. 5. Each of the angles is provided with a lug 5 by means of which the corner is suitably secured to the post P. The upper 60 angle 2 is also provided with a laterally projecting portion 6 to which an end rail 7 is secured.

A U-shaped member 8 is secured to the inside angle leg 2', lugs 9 on the U-shaped 65 member 8 and slots 10 in the angle legs 2' being provided for this purpose, the three walls a, b, c of the U-shaped member being spaced equal distances from the angle 2. A three-way space or pocket 11 is thus provided 70 between the U-shaped member 8 (hereafter called the inner shell) and the outer shell 1, which space is adapted to receive a side-rail 12 either in its normal position (Fig. 3) or inverted position (Fig. 6). 75 It will be observed that the side-rail 12 after being inserted into the space 11 does not contact with the inner faces of the angles 2, but, however, does engage at the end against the post P. The side-rail 12 is maintained 80 in abutting relation with the post P by means of a wedge or key 13, said key being inserted in registering slots 14, 14' in the outer and inner shells 1 and 8 and traversing a slot 15 in the side-rail 12. The disposition and size of the slots is such that when the key is inserted and forced downwardly it will wedge the side-rail 12 against the post P, thus holding the side-rail rigidly 85 against movement. A slot 15 is provided in 90 each leg of the side-rail so that the rail may be secured in either normal or inverted position (Figs. 3 and 6).

From the foregoing it will be seen that I have provided a corner-piece that will co-operate readily with the other parts of the bed making it a comparatively simple matter to assemble or take down the bed without the aid of tools.

Having described my invention I claim: 100
1. In combination with a structural member of a bed, a corner-fastening comprising an outer and an inner shell spaced apart to provide a three-way pocket, said shells having registering openings in the top and bottom walls thereof, said structural member also having openings, and a key adapted to co-operate with the openings in the shells and one of the openings in the structural member whereby the structural member may 105 110

be reversibly secured to the corner-fastening.

2. A corner-fastening comprising an outer shell and an inner shell, said outer shell being formed from a pair of angles secured together, the inner shell being formed of a single U-shaped member secured to one of said angles, said shells being spaced apart to provide a pocket between the shells, a side-rail adapted to be reversibly positioned in said pocket and means for securing said side-rail therein.

3. In combination with a bed-post and side rail to be secured thereto, a corner-

fastening comprising an outer and an inner shell, said shells being spaced apart to provide a pocket between the shells, said pocket being adapted to receive the side-rail in either normal or reversed position, there being a clearance between the outer surfaces of the side rail and inner surfaces of the shells, the shells and side-rail being provided with openings adapted to receive a key whereby the side-rail is locked in place in abutting relation with the bed-post.

25 In testimony whereof I affix my signature.

BENJAMIN H. JONES.
